FIRE EXTINGUISHING FOAM SYSTEM WITH
DELUGE VALVE CONTROL

Harry N. Rider, Youngstown, Ohio, assignor to
"Automatic" Sprinkler Corporation of America,
Youngstown, Ohio, a corporation of Delaware

Application March 18, 1950, Serial No. 150,477

5 Claims. (Class 169—4)

1

This invention relates to a fire extinguishing system and more particularly to such a system wherein water is mixed with a foam liquid concentrate to generate foam and the same directed into a protected area.

The principal object of the invention is the provision of a fire extinguishing foam system with a deluge valve control and capable of automatic actuation and shut-off.

A further object of the invention is the provision of an automatically actuated fire extinguishing foam system incorporating means for shutting off the operation of the system at such time as the foam liquid supply is exhausted.

A still further object of the invention is the provision of a simple and economical fire extinguishing foam system incorporating a simple automatically actuated deluge valve and exhaust heat responsive control means for automatically detecting a fire in a controlled location, mixing and delivering fire extinguishing foam to the said location and shutting off such operation at such time as the available supply of foam generating liquid is exhausted.

The fire extinguishing foam system with deluge valve control shown and described herein has been designed to provide a simple and efficient fire extinguishing apparatus particularly suited for application to various hazardous areas wherein inflammable materials are processed or used in processing other materials. The system disclosed herein utilizes a water supply as the principal fire extinguishing medium and mixes with the water supply a foam liquid concentrate such as known in the art to form a suitable fire extinguishing foam such as also known in the art. The foam is then directed onto the surface of the area protected.

The principal point of novelty in the disclosure is the deluge valve controlling the water supply to the foam liquid generator and distributor and the control of the deluge valve by an automatically operated device subject in operation to abnormal temperatures in the fire zone and capable of being controlled by suitable actuating means in the foam liquid supply source whereby the system will be shut down when the foam liquid supply is exhausted.

With the foregoing and other objects in view which will appear as the description proceeds, the invention resides in the combination and arrangement of parts and in the details of construction hereinafter described and claimed, it being understood that changes in the precise embodiment of the invention herein disclosed can be

2

made within the scope of what is claimed without departing from the spirit of the invention.

The invention is illustrated in the accompanying drawing, wherein:

5 Figure 1 is a side elevation of the fire extinguishing foam system with deluge valve control.

Figure 2 is a vertical section taken on line 2—2 of Figure 1.

10 Figure 3 is an enlarged cross sectional elevation taken on line 3—3 of Figure 1.

Figure 4 is an enlarged cross sectional elevation taken on line 4—4 of Figure 1.

15 Figure 5 is a vertical section taken on line 5—5 of Figure 4.

Figure 6 is a horizontal section taken on line 6—6 of Figure 1.

By referring to the drawings and Figures 1 and 2 in particular it will be seen that a foam system has been illustrated in connection with

20 a dip tank 10 comprising the flammable area to be controlled and that the system itself includes a water supply source 11. The dip tank 10 is provided with a foam distributor 13 located on one side thereof and the deluge valve 12 com-

25 municates with the foam distributor by way of a pipe 14 which includes a mixer 15. The mixer 15 is also in communication with a foam liquid supply tank 16 by way of a tube 17, the mixer 15 being adapted to pull foam liquid concentrate from the tank 16 as by Venturi action in the mixer 15 when water from the supply source 11 flows through the valve 12 and thus through the mixer 15 and into the foam distributor 13.

The deluge valve 12 is controlled by a release mechanism generally indicated by the numeral 18 and the release is subject to the remote operation as by a heat actuated device 19. The heat actuated device 19 is placed in communication with the release 18 by means of a tubular connecting member 20.

35 The release mechanism 18 is so arranged that to be operative, water from the supply source 11, by-passed through the appropriate elements of the deluge valve 12, is allowed to flow through a valve portion 18A of

40 the release mechanism and outwardly thereof through an exhaust pipe 21. A float control valve 22 located in the foam liquid supply tank 16 heretofore referred to and including a float

45 movable by the float level in the foam liquid supply tank 16 controls the exhaust pipe 21 which also communicates with a drain, not shown.

50 In operation, fire occurring in the dip tank 10, for example, actuates the heat actuated device 19 which in turn causes actuation of the

release 18. The release 18 opens a valve in the section 18A thereof, permits water from the supply source 11 to by-pass the actuating elements of the deluge valve 12 and thereby effect the opening of the clapper therein. The water causing such actuation flows through the exhaust pipe 21 and through the normally open valve 22 in the foam liquid supply tank 16 and thence to drain.

The water released by the deluge valve 12 flows through the pipe 14, the mixer 15 and into the foam distributor 13 on the tank 10. Simultaneously with such action, foam liquid is drawn into the mixer 15 through the tube 17 by a Venturi action in the mixer 15 so that the liquid entering the foam distributor 13 is properly proportioned and a suitable fire extinguishing foam is thus distributed from the distributor 13 over the surface of the dip tank 10, as best shown in Figure 2 of the drawings. The fire in the dip tank 10 is thus extinguished.

The foam liquid supply tank 16 is of a predetermined size or capacity to control the indicated hazard such as the dip tank 10 and the system is so designed that upon the exhaustion of the foam liquid supply from the tank 16, as by the operation just described, the float 23 will move downwardly and close the float control valve 22 and thereby shut off the flow of water through the exhaust pipe 21. Such action immediately results in the closing of the deluge valve 12 and hence the automatic shut off of the automatic foam generating system.

While the foregoing comprises a general description of the apparatus of the fire extinguishing foam system and its operation, the following relates to a description of the deluge valve 12 and the actuating release 18 and the mixer 15 which devices are essential to the operation of the system and which devices, and particularly the deluge valve 12, are new in the art of fire extinguishing systems of the foam generating and distributing type.

As heretofore referred to in connection with Figure 1 of the drawings, the water supply source 11 is controlled by a deluge valve generally indicated by the numeral 12. By referring to Figure 3 of the drawings an enlarged cross sectional detail of the deluge valve 12 may be seen. By referring thereto it will be observed that it includes an inlet orifice 24 into which the water supply 11 is delivered. A vertically movable clapper 25 is positioned for registry with the inlet 24 and is normally closed with respect thereto. The inlet 24 includes a releasable seat ring 26 and the clapper 25 includes radially spaced guide members 27 insuring alignment and proper setting of the clapper 25 on the seat ring 26. The clapper 25 includes a facing 28 of suitable material and the clapper 25 has a vertical passageway 29 therethrough. A flexible tube 29A is positioned in the passageway 29 and extends upwardly through a hollow stem 30 which is loosely secured to the uppermost portion of the clapper 25 by a threaded retaining ring 31.

The hollow stem 30 extends upwardly a substantial distance above the clapper 25 and the flexible tube 29 extends upwardly therethrough to establish a flexible connection with a disc 32 which is positioned immediately beneath a flexible diaphragm 33 the area of which is greater than the area of the clapper 25. The disc 32 is secured to the diaphragm 33 as an upward extension 34 of the disc passes through an opening in the diaphragm 33 and is provided

with a retaining ring 35 and a nut 36. The upward extension 34 of the disc 32 has a restricted passageway 37 therein establishing communication with a chamber 38 above the said diaphragm 33 and in the valve body 12A. Communication is thus established from the inlet 24 through the clapper 25, the flexible connection 29A in the hollow stem 30 and the passageway 37 with the chamber 38. The valve body 12A is circular and secured at its periphery to a similar valve body 12B which in turn is threadably mounted on the uppermost portion of the valve 12 heretofore referred to and which encloses the clapper 25.

The valve body 12 has an outlet orifice 39 by means of which communication is established with the pipe 14 heretofore referred to. The valve body 12A has a chamber 40 extending upwardly therein and which chamber 40 communicates with the valve portion 18A of the release mechanism 18 as illustrated in Figure 1 of the drawings and more specifically in Figures 4 and 5 of the drawings.

Still referring to Figure 3 of the drawings it will be seen that a coil spring 41 is positioned about the hollow stem 30 of the clapper 25 and in a chamber 42 in the valve body 12B, the lower portion of the coil spring resting on a shoulder of the valve body 12C and the upper portion of the coil spring 41 engaging the bottom of the disc 32 which is thereby urged upwardly by the spring 41.

In operation, water from the supply 11 flows through the inlet 24 upwardly through the passageway 29 and the clapper 25 and upwardly through the hollow stem 30 and into the chamber 38 within the valve body 12A. The water pressure flexes the diaphragm 33 downwardly, as shown in Figure 3 of the drawings, which action moves the disc 32 and the hollow stem 30 and the clapper 25 downwardly so that the clapper 25 seats on the seat ring 26 and thus closes the inlet orifice 24. The valve 12 is thus maintained in closed position by water pressure from the supply 11. The chamber 40 and its passageway to the valve portion 18A of the release mechanism is ordinarily closed by the valve 18A of the release mechanism 18, which action permits the building up of sufficient pressure in the chamber 38 to effect the action just described.

In order that the apparatus controlling the flow of water through the chamber 40 and the valve portion 18A of the release mechanism 18 may be understood, the same is illustrated in Figures 4 and 5 of the drawings and by referring thereto it will be seen that the release 18 comprises a device responsive in operation to pneumatic pressure generated in the fire zone for opening a valve, generally indicated by the numeral 18A and formed in the lower portion of the release 18. The valve 18A is best illustrated in Figure 5 of the drawings where it will be seen in communication with the upper portion of the valve body 12B and the chamber 40 heretofore referred to in connection with the preceding description thereof.

The valve portion 18A includes an inlet 42 and an outlet 43, the inlet 42 threadably receiving the uppermost portion of the valve body 12B and the outlet 43 threadably receiving the exhaust pipe 21 heretofore referred to. A valve element 44 is reciprocally positioned in a valve chamber 45 and is normally urged to closed position on the inlet 43 by a coil spring 46. The

coil spring 46 is engaged against the lower end of the vertical lever 47 which extends upwardly out of the chamber 44 and into the release mechanism 18 and is sealed with respect to the valve portion 18A by suitable resilient gaskets 48 and 49. The vertical lever 47 is pivoted at a point 50 so that tilting movement imparted to the lever 47 will open or close the valve element 44 with respect to the outlet orifice 43. A coil spring 51 normally urges the valve lever 47 to open position with respect to the valve element 44 and the lever 47 is restrained against such movement by a tiltable latch 52 which is engaged against one side of the tapered upper end of the lever 47 as best shown in Figure 5 of the drawings.

The tiltable latch 52 is pivoted by a pivot pin 53 to a supporting bracket 54 forming an extension on a diaphragm case 55, as best shown in Figure 4 of the drawings, and the tilting latch 52 is normally held in engagement with the lever 47 by a movable detent 56 which in turn is pivoted as at 57 to projections on the diaphragm case 55 and the opposite end of the detent 56 is positioned adjacent a pin 58 which in turn is actuated by a diaphragm (not shown) in the diaphragm case 55. A spring 59 normally holds the detent 56 in vertical position, as best shown in Figure 4 of the drawings, and the device is operative at such time as increased air pressure in the case 55, as occasioned by increased air pressure in a connected heat actuated device such as shown in Figure 1 and indicated by the numeral 19, moves the diaphragm in the case against the pin 58 so as to move the detent 56 out from under the tiltable lever 52 and thereby permit it to release the lever 47 which will then open the valve element 44.

The heat actuated device 19 is placed in communication with the diaphragm case 55 by way of the communicating tube 20, a portion of which is cut away, as shown in Figure 4 of the drawings, in order that the remainder of the mechanism may be seen. The release mechanism includes a reset pin 60, the innermost end of which may be engaged against the lever 47 to move the same to reset position, as shown in Figure 5 of the drawings, and the outermost end of the pin 60 extends outwardly through an apertured plate 61 secured to the housing of the release mechanism 18 and the same is enclosed in a resilient jacket 62. It will thus be seen that at such time as fire in the area controlled (such as the dip tank 10 as seen in Figure 1 of the drawings) actuates the heat actuated device 19, the deluge valve 12 is opened and the system is actuated through the following action. The resulting pneumatic impulse or increase of pressure conveyed to the case 55 by the tubing 20 will move the diaphragm (not shown) against the pin 58 which in turn moves the detent 56 from under the tiltable latch 52 and thus frees the lever 47 which is then moved by the spring 51 to move the valve element 44 to open position with respect to the outlet 43. When this occurs, fluid pressure in the chamber 38 of the valve body 12A is exhausted through the exhaust pipe 21 more rapidly than it can be replaced through the restricted passageway 37, which action permits the spring 41 to elevate the disc 32 and hence the clapper 25 and thus permit water to flow freely from the supply source 11 through the valve 12 and through the pipe 14 to the mixer 15 and the distributor 13 on the dip tank 10.

By referring again to Figure 1 of the drawings it will be observed that when such action occurs, the mixer 15 actuates to draw foam liquid concentrate through the tube 17 from the foam liquid tank 16. This is occasioned by the existence in the mixer 15 of a venturi 63 as may be seen by referring to Figure 6 of the drawings. The mixing of the foam liquid concentrate introduced by the venturi 63 into the pipe 14 results in the generation of suitable fire extinguishing foam which is then introduced into the distributor 13 from whence it is discharged into the dip tank 10 as best shown in Figure 2 of the drawings.

Still referring to Figure 1 of the drawings it will be seen that the exhaust pipe 21 extends through a portion of the foam liquid supply tank 16 and that it is controlled by a float operated valve 22 as heretofore referred to. The float operated valve includes the float 23 responsive to the level of liquid in the tank 16 and the exhaust pipe 21 extends from the float control valve 22 to a drain or other point of disposal.

During the operation of the system hereinbefore described, water flowing upwardly through the hollow stem 30 of the valve 12, into the chamber 38 and through the chamber 49 in the valve body 12A continues to flow through the open valve portion 18A of the release mechanism 18 and through the exhaust pipe 21 and through the float control valve 22 to a point of discharge. This action maintains the valve 12 in open position so that the water flows freely from the supply 11 to the pipe 14.

At such time as the supply of foam liquid in the tank 16 is exhausted the float 23 will move downwardly until it reaches its lowermost position where it will close the valve 22 and stop the flow of water through the pipe 21. This will immediately result in the building up of pressure in the exhaust pipe 21, the valve 18A of the release mechanism 18 and more importantly in the chamber 38 in the valve body 12A. Such building up of pressure therein flexes the diaphragm 33 downwardly and moves the hollow stem 30 downwardly which in turn moves the clapper 25 downwardly to close the inlet orifice 24 of the valve 12 and thus shutting off the source 11 and preventing further flow of water.

Thus the fire extinguishing foam system with deluge valve control disclosed herein is entirely automatic in its operation as such operation is initiated by fire in the area supervised, as heretofore explained in connection with the heat actuated device 19 and the release 18 which is responsive thereto and at such time as the foam liquid concentrate is exhausted from the tank 16 the system automatically shuts off and prevents further flooding of the controlled area. In cases of dip tanks normally holding inflammable liquid, this is a valuable and novel action as a predetermined amount of foam liquid can be supplied the tank 16 and which amount is sufficient only to generate enough foam to cover the dip tank and thereby prevent the flooding of the dip tank which would otherwise result in spilling of the inflammable liquid of the dip tank into the working area thereabout.

It will thus be seen that the several objects of the invention have been met by the system disclosed herein and that an efficient, simply constructed automatic fire extinguishing foam system with deluge valve control has been disclosed.

Having thus described my invention, what I claim is:

in combination an automatic pressure responsive deluge valve in communication with a water supply source and distributing piping, a mixer in said distributing piping for introducing foam liquid thereinto; and a foam liquid supply in communication with said mixer, a release mechanism controlling said deluge valve and including a control valve in pressure venting communication with said pressure responsive deluge valve, thermostats in a fire zone, said release mechanism responsive in operation to said thermostats, the said deluge valve responsive in opening operation to the opening of said control valve, a float operated valve in communication with said control valve and responsive in operation to the presence and absence of said foam liquid supply, said deluge valve responsive in closing operation to the closing of said control valve and to the closing of said float operated valve whereby the float operated valve will close and the system will shut off when the foam liquid supply is exhausted.

2. A fire extinguishing foam system comprising in combination a deluge valve in communication with a water supply source and distributing piping, said deluge valve including a clapper normally closed by fluid pressure from said water supply source and means urging the said clapper to open position responsive in operation to loss of said fluid pressure, a mixer in said distributing piping for introducing foam liquid thereinto; and a foam liquid supply in communication with said mixer, a release mechanism controlling said deluge valve and including a control valve in pressure releasing communication with said deluge valve, thermostats in a fire zone, said release mechanism responsive in operation of said thermostats, the said deluge valve responsive in opening operation to the opening of said control valve, a liquid level responsive valve in communication with said control valve and responsive in operation to the liquid level of said foam liquid supply, said deluge valve responsive in closing operation to said liquid level responsive valve whereby the liquid level responsive valve will close and said system will shut off when the foam liquid supply is exhausted.

3. A fire extinguishing foam system including a deluge valve in communication with a water supply source and distributing piping, said deluge valve including a clapper normally closed with respect to said water supply source, a fluid pressure chamber, a flexible wall in said chamber and means connecting said flexible wall and said clapper and means establishing restricted communication between said water supply source and said fluid pressure chamber, spring means normally urging the said clapper toward open position and a valve for venting fluid pressure from said fluid pressure chamber to permit the said spring means to open said clapper, a float operated valve in communication with said valve, a

mixer in said distributing piping for introducing foam liquid thereinto and a foam liquid supply in communication with said mixer, said float valve responsive in operation to the level of the said foam liquid supply.

4. An automatic foam generating fire extinguishing system including an automatic valve in communication with a water supply source, a foam liquid supply, a foam mixer and a foam distributor, means establishing communication between said automatic valve and said foam mixer, and means establishing communication between said foam mixer and said foam distributor, secondary means establishing communication between said mixer and said foam supply, a release mechanism controlling said automatic valve, said release mechanism including an exhaust pipe for venting operating fluid pressure from said automatic valve and a float operated valve in said exhaust pipe and subject in operation to the level of the said foam liquid supply, a thermostat in a fire zone in communication with said release mechanism, said release mechanism responsive in operation to said thermostat whereby the system is responsive in starting operation to fire in the fire zone and responsive in ceasing operation to the exhaustion of said foam liquid supply.

5. A fire extinguishing foam generating system comprising an automatic pressure actuated valve, a water supply source controlled by said automatic valve and a foam mixer in communication with said automatic valve and with a foam distributor, a container for a foam liquid supply, a float operated valve, said float being in said container, said float operated valve responsive in operation to movement of said float in said foam liquid supply, and means establishing communication between said foam container and said mixer, the said mixer including a venturi acting to move foam liquid from the said container when the said mixer is in open communication with the said water supply, release means for said automatic valve, a thermostat in a fire zone connected to said release means, said release means responsive in operation thereto, and means interconnecting said float operated valve with said release means, said automatic valve responsive in closing to said float operated valve whereby the withdrawal of foam liquid from the said container actuates said float operated valve and closes said automatic valve.
